UNITED STATES PATENT OFFICE.

FRANK P. MADRESS, OF PANAMA, CANAL ZONE.

PIPE.

1,291,053.

Specification of Letters Patent. Patented Jan. 14, 1919.

Application filed March 21, 1917. Serial No. 156,351.

To all whom it may concern:

Be it known that I, FRANK P. MADRESS, a citizen of the United States, residing at Panama, Canal Zone, have invented certain new and useful Improvements in Pipes, of which the following is a specification.

My invention relates to improvements in smoking pipes, and it consists in the constructions, combinations, and arrangements herein described and claimed.

An object of my invention is to provide a smoking pipe embodying a novel nicotin collecting vessel and an insertible smoke cooling member including a spiral groove whereby the nicotin is received in the vessel and the smoke is cooled while passing through the groove.

Another object of the invention is to provide a smoking pipe including the elements and features above enumerated, the construction of the pipe permitting ready assembling for cleaning.

Other objects and advantages will appear from the following specification, reference being had to the accompanying drawing in which:

Figure 1 is a central longitudinal section of a pipe illustrating the nicotin collecting vessel in section and the smoke cooling member in elevation.

Fig. 2 is a section on the line 2—2 of Fig. 1, and

Fig. 3 is an inverted perspective view of the nicotin receiving vessel.

In carrying out one of the features of my invention, it will be observed that I provide a cylindrical plug 1. The plug 1 has a spiral groove 2 formed in its periphery or surface as illustrated in Fig. 1. The cylindrical plug 1 is insertible in the bore 3 of the pipe stem 4 which is integral with the pipe bowl 5. A passage 6 establishes communications between the bowl 5 and the bore 3 of the stem 4, a shoulder 7 being formed at the juncture of the passage 6 and bore 3 adjacent which the cylindrical plug 1 rests when the parts are assembled.

The outer end of the spiral groove 2 of the cylindrical plug 1 terminates coaxially of the plug 1 and is internally screw threaded as indicated at 8. A screw block 9 is screwed into engagement with the screw threaded portion 8 and includes an enlarged threaded portion on which the mouth piece 10 of the pipe is screwed. The screw block 9 has a

central smoke bore 9' which communicates with the spiral groove 2 as plainly shown in the drawings, the smoke bore in the screw plug 9 also communicating with the bore 10' in the mouth piece 10 when the parts 60 are assembled as shown in Fig. 1.

A nicotin receiving vessel 11 is located at the bottom of the bowl 5 adjacent to the passage 6. The vessel 11 includes a drum-like upper portion 12 which has a plurality of perforations 13. That portion of the vessel 11 adjacent to the drum-like upper portion 12 is of a larger diameter than the main drum-like portion thereof. It will be seen that the portion 12 is of such dimensions that it snugly engages the lower portion of the bowl 5. The portion 14 of the vessel 11 has a laterally extending neck 15 which is adapted to be projected into the passage 6. The neck 15 has an upwardly curved beak 16 which is projected into the inner end of the spiral groove 2 of the cylindrical plug 1. For the purpose of accomplishing the connections above referred to, the spiral groove 2 terminates coaxially of the cylindrical plug 1 at the place adjacent the connection with the beak 16.

The construction of the pipe having been explained, the method of assembling the parts is as follows:

Assuming the various parts above described are to be disassembled, the cylindrical plug 1 is inserted in the bore 3 of the pipe stem 4. The nicotin receiving vessel 11 is now placed within the bowl 5 of the pipe and adjusted until the beak 16 enters the inner end of the spiral groove 2 adjacent to the shoulder 7.

The connections between the receptacle 11 and the cylindrical plug 1 having been made, the mouth piece 10 is screwed onto the screw block 9 until it tightly binds against the adjacent end of the pipe stem 4. It will be observed that the upwardly curved beak 16 froms the binding member which holds the 100 cylindrical plug and the mouth piece 10 against accidental displacement.

In the use of the pipe the nicotin from the tobacco contained in the bowl 5 will be collected in the vessel. It will be noted that 105 the beak 16 branches from the neck 15 at a place adjacent the upper portion thereof. When it becomes necessary to clean the pipe, the mouth piece 10 is removed so that the cylindrical plug member may subse- 110

quently be removed. The vessel 11 is then taken from the bowl by turning it in such a manner that the beak 16 disengages the adjacent groove end 2. Upon this disengagement of the receptacle 11, the cylindrical plug 1 may readily be removed and all of the parts conveniently cleaned.

Having thus described my invention, what I claim is:

- 10 In a device of the class described, the combination of a pipe including a bowl having a hollow stem leading therefrom, a shoulder formed upon said stem, a nicotine receiving vessel comprising a drum-like upper portion and a drum-like lower portion, said drum-like upper portion having apertures formed therein, thus permitting refuse to pass into said vessel, a neck extend-
- 15

ing from said drum-like lower portion in a plane below the drum-like upper portion, an upwardly curved beak formed upon the outer end of said neck in a plane above the bottom of said neck, and means carried within said hollow stem and engaging said beak for holding said nicotine receiving vessel against accidental displacement, said means bearing upon said shoulder for firmly holding said vessel and said means in respective position.

In testimony whereof I affix my signature 30 in presence of two witnesses.

FRANK P. MADRESS.
